(57) **CLAIM**

The ornamental design for the light tunnel for electrosurgical pencil, as shown and described.

DESCRIPTION

FIG. 1 is a perspective view of the light tunnel for electrosurgical pencil.

FIG. 2 is a first side view of the light tunnel for electrosurgical pencil.

FIG. 3 is a second side view of the light tunnel for electrosurgical pencil.

FIG. 4 is a first end view of the light tunnel for electrosurgical pencil.

FIG. 5 is a second end view of the light tunnel for electrosurgical pencil.

FIG. 6 is a top view of the light tunnel for electrosurgical pencil.

FIG. 7 is a bottom view of the light tunnel for electrosurgical pencil; and,

FIG. 8 is a perspective view of the light tunnel for electrosurgical pencil as located for use.

The broken lines depict non-claimed subject matter and form no part of the claimed design.

1 Claim, 5 Drawing Sheets
